UNITED STATES PATENT OFFICE.

GEORGE SEIGFRIED BRUSH, OF ZANESVILLE, OHIO.

DESIGN FOR A RADIOCABINET.

Application filed July 13, 1926. Serial No. 18,353. Term of patent 7 years.

To all whom it may concern:

Be it known that I, GEORGE SEIGFRIED BRUSH, a citizen of the United States, residing at Zanesville, in the county of Muskingum and State of Ohio, have invented a new, original, and ornamental Design for a Radiocabinet, of which the following is a specification, reference being had to the ac-

companying drawing, forming part thereof.

Fig. 1 is a plan view of a radiocabinet showing my new design.

Fig. 2 is a side elevation of the same.

I claim:

The ornamental design for a radiocabinet as shown.

GEORGE SEIGFRIED BRUSH.
